Primary Examiner—Alan P. Douglas*Assistant Examiner*—Robin V. Taylor*Attorney, Agent, or Firm*—Ian F. Burns[57] **CLAIM**

The ornamental design for a fluid manifold, as shown and described.

DESCRIPTION

FIG. 1 is a side perspective view of the fluid manifold of the present invention;

FIG. 2 is a right side elevational view of the fluid manifold of the present invention, the left side elevational view being a mirror image thereof;

FIG. 3 is a front elevational view of the fluid manifold of the present invention;

FIG. 4 is a rear elevational view of the fluid manifold of the present invention;

FIG. 5 is a top plan view of the fluid manifold of the present invention; and,

FIG. 6 is a bottom plan view of the fluid manifold of the present invention.

The claimed design is shown fragmented to indicate indeterminate length.
